UNITED STATES PATENT OFFICE

OTTO HOOVER, OF EAST ST. LOUIS, ILLINOIS

AUXILIARY APPARATUS FOR SETTING AIR BRAKES

Application filed November 19, 1929. Serial No. 408,357.

This invention relates to a brake applying or setting apparatus for freight and other cars, and has for one of its objects to provide a novel apparatus of this character which shall be especially adapted to be used during the shifting of freight cars and through the medium of which the brakes of a free car may be set without danger to the brakeman and in a much shorter time and more positively than they could be set through the medium of one of the hand wheels of the car.

The invention has for a further object to provide an apparatus of the character stated which shall be adapted, when released, to function automatically to effect the setting of the brakes and which may be easily and quickly released by the brakeman from a position on the roof, or on one of the stirrups, or on one of the platforms of the car.

The invention has for a further object to provide an apparatus of the character stated which shall be simple, durable and highly efficient, which may be manufactured and sold at a comparatively low cost, and which may be readily mounted upon the body of the car and connected to the brake mechanism thereof.

With the foregoing and other objects in view, the nature of which will appear as the description proceeds, the invention consists in the construction, combination and arrangement of parts hereinafter fully described and claimed, and illustrated in the accompanying drawing, wherein:

Figure 1 is a view in side elevation of a fragmentary portion of a freight car equipped with a brake setting apparatus constructed in accordance with my invention;

Figure 2 is a view in end elevation of the car and brake setting apparatus;

Figure 3 is a sectional view on an enlarged scale taken on a vertical plane extending centrally through the brake setting apparatus;

Figure 4 is a sectional view taken on the horizontal plane indicated by the line 4-4 of Figure 3;

Figure 5 is a sectional view taken on the horizontal plane indicated by the line 5-5 of Figure 2;

Figure 6 is a view in side elevation illustrating one of the brackets for supporting the levers of the brake setting apparatus; and

Figure 7 is a sectional view illustrating the manner in which certain of the levers are pivotally and slidably connected to the brackets.

Referring in detail to the drawings, 1 designates the body of a freight car of the usual construction. 2 designates two of the stirrups, 3 two of the series of ladder rounds, and 4 one of the end platforms of the car. 5 designates a brake cylinder which is secured to the under side of the car body 1, 6 a lever which is pivotally connected, as at 7, to the piston rod 8 of the cylinder, and 9 rods which connect the lever to the floating levers attached to the brake beams. The cylinder 5, levers 6 and rods 9 constitute parts of an air brake mechanism of the type usually used on freight cars and the part 6 is the primary lever of the brake.

The brake applying apparatus constituting the subject matter of this application, comprises a cylinder 10 which is secured in an upright position upon an end of the car body 1. The cylinder 10 is secured in place by bolts 11 which pass through the end of the car body 1 and through brackets 12 fixed to the rear side of the cylinder and extending laterally beyond the cylinder. The cylinder 10 is provided at its lower end with an outwardly directed annular flange 13, and this end of the cylinder is closed by a plate 14 which is removably secured to the flange by bolts 15. The cylinder 10 is provided at diametrically opposite sides thereof with channeled guides 16 and 17 which extend from the upper to the lower ends of the cylinder and communicate with the cylinder.

A casing 18 is formed integrally with the cylinder 10, and it extends laterally from the cylinder at a point centrally between the ends thereof. The casing 18 is provided with a cap or upper section 19 which is removably secured in place by bolts 20. Alined bearings 21 and 22, and alined bearings 23 and 24 are formed in the front and rear walls of the casing 18 and its cap section 19. The guide

16 is provided with a lateral extension 16^a which is arranged within the casing 18 and is provided with bearing openings 25 which register with the bearings 21 and 22. The 5 front walls of the casing 18 and its cap section 19 are provided with an opening 26 which registers with the bearings 23 and 24, and said bearings are provided with annular recesses 23^a and 24^a, respectively.

10 A hollow piston body 27 is slidably mounted in the cylinder 10, and it is closed at its upper and open at its lower end. Ribs 28 and 29 which are arranged at the outer side of the piston 27 and extend from the lower 15 to the upper end thereof, fit in the guides 16 and 17 and serve, in conjunction with the guides, to prevent the piston from having any tilting movement with respect to the cylinder 10. The rib 28 is provided with rack teeth 20 30 with which meshes a pinion 31 fixed to a shaft 32 journaled in the bearings 21, 22 and 25. The rib 29 is provided with anti-friction rollers 33 which contact with the outer lateral wall of the guide 17.

25 A pull rod 34 is arranged axially within the piston 27 and has its upper end secured, as at 35, to the upper end wall 27^a of the piston. The rod 34 extends downwardly through the head 14 of the cylinder 10. A heavy coil 39 spring 36 is arranged within the piston 27, and bears at its lower end upon the head 14 of the cylinder 10 and at its upper end against the end 27^a of the piston.

The piston 27 is considerably shorter than 35 the cylinder 10, and it normally occupies a position in the lower end of the cylinder with the spring 36 under compression. The piston 27 is adapted to be moved into and held in its lowered position against the power 40 of the spring 36 by means which comprise, in addition to the rack bar 28, pinion 31 and shaft 32, a shaft 37 journaled in the bearings 23 and 24, a pinion 38 loose on the shaft 37 and meshing with a pinion 39 fixed on the 45 shaft 32, a male clutch element 40 fixed to the pinion 38, and a female clutch element 41 splined to the shaft 37. The shaft 37 is provided at its rear end with an annular flange 42 which fits in the groove 24^a of the bearing 24 and serves to hold the shaft against 50 endwise displacement. The pinion 38 is provided with an annular flange 43 which fits in the groove 23^a of the bearing 23 and serves to hold the pinion against endwise movement 55 with respect to the shaft 37. The shaft 37 extends forwardly through the opening 26 of the casing 18, and is provided at its outer or front end with a hand wheel 44. A ratchet wheel 45 is fixed to the shaft 37 forwardly of the casing 18, and a pawl 46 pivoted intermediate its ends, as at 47, to the front side of the casing 18, normally engages the ratchet wheel and serves, when the clutch members 40 and 41 are in engagement, to 60 releasably hold the piston 27 in its lowered

position. The piston 27 is adapted to be moved into its lowered position through the medium of the hand wheel 44 when the clutch members 40 and 41 are in engagement. The outer spokes of the hand wheel 44 are spaced 70 apart sufficiently to permit the brakeman to place his foot between them should he find it necessary to do so in order to effect the lowering of the piston 27 against the power of the spring 36.

75 A foot lever 48 which is pivoted at one end, as at 49, upon the platform 4, and which is connected by a rod 50 to the pawl 46, provides means by which the pawl may be swung out of engagement with the ratchet wheel 45 to effect the release of the shaft 37 when it is desired to lower the piston 27.

80 The clutch member 41 is provided with a sleeve 51 which extends axially therefrom and surrounds the shaft 37. The sleeve 51 is provided with inner ribs 52 which extend longitudinally thereof and engage in grooves 53 extending longitudinally of the shaft 37, the ribs connecting the clutch member 41 to the shaft for rotation therewith and for adjustment longitudinally thereof. The clutch member 41 is adapted to be moved into and out of engagement with the clutch member 40 through the medium of a rod 54 which is rotatably supported by bearings 55 along 85 side the cylinder 10. The bearings 55 are secured to the end of the car. The rod 54 extends from the upper end of the cylinder 90 95 100 105 110 115 120 125 130

10 A sleeve 51 surrounds the shaft 37 and is provided with inner ribs 52 which extend longitudinally thereof and engage in grooves 53 extending longitudinally of the shaft 37, the ribs connecting the clutch member 41 to the shaft for rotation therewith and for adjustment longitudinally thereof. The clutch member 41 is adapted to be moved into and out of engagement with the clutch member 40 through the medium of a rod 54 which is rotatably supported by bearings 55 along side the cylinder 10. The bearings 55 are secured to the end of the car. The rod 54 extends from the upper end of the cylinder 10 to a point below the lower end thereof, and is provided at its upper and lower ends with crank arms or handles 56 which are terminally equipped with grips 57. A rack sleeve 58 surrounds the clutch sleeve 51, and it is rotatably connected to the clutch sleeve by annular flanges 59 formed on the clutch sleeve and engaging in grooves 60 formed in the rack sleeve. The rack sleeve 58 is made of sections to permit it to be applied to the clutch sleeve 51, and the sections thereof are secured together by bolts 61. The rack teeth 62 of the rack sleeve 58 extend longitudinally of the sleeve and mesh with a segmental gear 63 which is fixed to a shaft 64 arranged at right angles to the shaft 37.

The rack sleeve 58 is provided above and below its rack teeth 62 with flanges 65 which contact with the upper and lower side of the pinion 63 to prevent the sleeve from turning out of engagement with the pinion. The shaft 64 is journaled at its lower end in a step bearing 66 carried by the bottom of the casing 18, and it extends through and beyond a bearing 67 formed in the top of the cap 19 for the casing.

125 A crank arm 68 carried by the rod 54 and a crank arm 69 carried by the shaft 64, and a link 70 connecting the crank arms, constitute means for establishing an operative connection between the rod and shaft. This connection is such that when the rod 54 is turned 130

in one direction, the pinion 63 is moved in a direction to carry the clutch element 41 out of engagement with the clutch element 40, with the result that the piston 27 will be freed for upward movement by the spring 36. This connection is also such that when the shaft 54 is moved in its opposite direction, the pinion 63 is turned in a direction to move the clutch member 41 into engagement with the clutch member 40. The rod 54 may be readily turned through the medium of either of its handles 56 by a brakeman occupying a position upon the roof of the car or standing upon the stirrup 2 or upon one of the ladder rounds 3. The pinion 63 is of the split type to permit of its easy engagement with the angular portion 64^a of the shaft which is provided therefor, and the pinion is adapted to be secured on such portion of the shaft by a bolt 71.

The rod 34 of the piston 27 is connected to the brake lever 6 by means which comprise front levers 72 and 73 and rear levers 74 and 75, which are of angular formation. The levers 72 and 73 are carried by a bracket 76 which is secured, as at 77, to the bottom of the car body 1 and extends longitudinally of the car. The lever 72 is pivoted, as at 78, to the front end of the bracket 76, and has one arm pivoted, as at 79, to the lower end of the piston rod 34. The pivot 78 occupies a fixed position on the bracket 76, and the other arm of the lever 72 is pivotally connected, as at 80, to one arm of the lever 73. The lever 73 is pivotally and slidably connected to the bracket 76, as at 81, and the other arm thereof is secured by a link 82 to one arm of the lever 74. The levers 74 and 75 are carried by a bracket 83 which is secured to the under side of the car body 1 and extends longitudinally thereof, and is located directly in rear of but slightly above the bracket 76. The lever 74 is pivoted, as at 84, to the bracket 83, and the lever 75 is pivotally and slidably connected to the bracket, as at 85, the pivot 84 occupying a fixed position on the bracket 85. The bracket 76 is provided with guide slots 86 for the pivot 81, and the pivot is provided with rollers 87 which move in the slot and insure the free sliding movement of the pivot. The brackets 83 are provided with guides 88 for the pivot 85 and the pivot is provided with rollers 89 which fit in the guides and insure the free turning and sliding movement of the pivot. The levers 72—75 and a link 90 connect the piston rod 34 to the brake levers 6 in such a manner that the upward movement of the piston rod results in the application of the brakes and the downward movement of the piston rod results in the retraction of the brakes.

The levers 74 and 75, during the upward movement of the piston 27, serve to rapidly take up slack in the brake rigging, with the result that the brakes will be applied as the

result of a short upward stroke of the piston and before the spring 36 has fully expanded.

In practice, when it is desired to compress the spring 36, the piston 27 is moved downwardly in the cylinder 10. The piston 27 is adapted to be moved in this direction, when the clutch member 41 is in engagement with the clutch member 40, through the medium of the hand wheel 44. During the turning of the hand wheel 44, the pawl 46 is maintained out of engagement with the ratchet wheel 45 through the medium of the foot lever 48. After the piston 27 has been moved into its normal lowered position, the pawl 46 is released to latch the piston in this position. The brakes are now released, and when it is desired to apply the brakes, it is only necessary to turn the rod 54 in a direction to move the clutch member 41 out of engagement with the clutch member 40, and this may be done through the medium of either of the handles 56. The movement of the clutch member 41 out of engagement with the clutch member 40 frees the piston 27 for upward movement by the spring 36, and this movement of the piston results in the brake lever 6 being pulled in a direction to apply the brakes. When it is desired to release the brakes, it is only necessary to move the clutch member 41 into engagement with the clutch member 40 and move the piston 27 downwardly.

While I have described the principle of the invention, together with the structure which I now consider the preferred embodiment thereof, it is to be understood that the structure shown is merely illustrative and that such changes may be made, when desired, as fall within the scope of the invention as claimed.

I claim:

1. In combination, the brake cylinder and the primary lever of an air brake, a second cylinder, a piston slidably mounted in said second cylinder, means connecting the piston to the lever to permit the movement of the piston in one direction to rock the lever in brake applying direction, a spring adapted to move the piston in said direction, means for moving the piston in the opposite direction to compress the spring, and means releasably holding the piston against movement upon the spring.

2. In combination, the brake cylinder and the primary lever of an air brake, a second cylinder, a piston slidably mounted in said second cylinder, a take-up mechanism connected to the lever, means connecting the piston to the take-up mechanism to permit the movement of the piston in one direction to rock the lever in brake applying direction, a spring adapted to move the piston in said direction, means for moving the piston in the opposite direction to compress the spring, and means releasably holding the piston against movement by the spring.

3. In combination, the brake cylinder and the primary lever of an air brake, a second cylinder, a piston slidably mounted in said second cylinder, first and second connected angular levers, means supporting said first lever for movement about a fixed axis and supporting said second lever for movement about a shifting axis, means connecting said second lever to the primary lever, means connecting the piston to said first lever to permit the movement of the piston in one direction to rock the lever in brake applying direction, a spring adapted to move the piston in said direction, a rack bar carried by the piston, first and second shafts, pinions fixed to said first shaft and of which one meshes with the rack bar, a pinion loose on said second shaft and meshing with the other pinion on said first shaft, a clutch for connecting said loose pinion to said second shaft, clutch operating means, and means engaging said second shaft to releasably hold the piston against movement by the spring when said loose pinion is clutched to said second shaft.

4. In combination, the brake cylinder and the primary lever of an air brake, a second cylinder, a piston slidably mounted in said second cylinder, a take-up mechanism connected to the lever, first and second angular levers, means supporting said first lever for movement about a fixed axis and said second lever for movement about a shifting axis, means connecting said second lever to the take-up mechanism, means connecting said first lever to the piston, a spring bearing against the piston, means for moving the piston in one direction to compress the spring, and means releasably holding the piston against movement by the spring.

5. In combination, a brake cylinder and the primary lever of an air brake, a second cylinder, a piston slidably mounted in said second cylinder, first and second angular levers pivotally connected, means supporting said first lever for movement about a fixed axis and said second lever for movement about a shifting axis, means connecting said second lever to the primary lever, third and fourth angular levers pivotally connected, means supporting said third lever for movement about a fixed axis and said fourth lever for movement about a shifting axis, means connecting said first and fourth levers, means connecting said third lever and piston, a spring bearing against the piston, means for moving the piston to compress the spring, and means releasably holding the piston against movement by the spring.

6. In combination, the brake cylinder and the primary lever of an air brake, a second cylinder, a piston slidably mounted in said second cylinder, means connecting the piston to the lever to permit the movement of the piston in one direction to rock the lever in brake applying direction, a spring adapted to move the piston in said direction, means for moving the piston in the opposite direction of the compressed spring and adapted to releasably hold the piston against movement by the spring, a release rod, and means connecting the release rod to said first means.

65 7. In combination, a brake cylinder and

the primary lever of an air brake, a second cylinder, a piston slidably mounted in said second cylinder, means connecting the piston to the lever to permit the movement of the piston in one direction to rock the lever in brake applying direction, a spring adapted to move the piston in said direction, a rack bar carried by the piston, first and second shafts, pinions fixed to said first shaft and of which one meshes with the rack bar, a pinion loose on said second shaft and meshing with the other pinion on said first shaft, a clutch for connecting said loose pinion to said second shaft, clutch operating means, and means engaging said second shaft to releasably hold the piston against movement by the spring when said loose pinion is clutched to said second shaft.

8. In combination, the brake cylinder and the primary lever of an air brake, a second cylinder, a piston slidably mounted in said second cylinder, means connecting the piston to the lever to permit the movement of the piston in one direction to rock the lever in brake applying direction, a spring adapted to move the piston in said direction, first and second shafts, pinions fixed to said first shaft and of which one meshes with the rack bar, a pinion loose on said second shaft and meshing with the other pinion of said first shaft, a clutch for connecting the loose pinion to said second shaft, clutch operating means arranged outside of the cylinder, and means engaging said second shaft and adapted to hold the piston against movement by the spring when said loose pinion is clutched to said second shaft.

9. In combination, the brake cylinder and the primary lever of an air brake, a second cylinder, a piston slidably mounted in said second cylinder, means connecting the piston to the lever to permit the movement of the piston in one direction to rock the lever in brake applying direction, a spring adapted to move the piston in said direction, first and second shafts, pinions fixed to said first shaft and of which one meshes with the rack bar, a pinion loosely mounted on said second shaft and meshing with the other pinion of said first shaft, a clutch member carried by the loose pinion, a clutch member splined to said second shaft, a sleeve rotatably connected to said second clutch member and provided with a rack bar, a pinion meshing with the rack bar, a shaft upon which said pinion is journaled, a rod rotatably supported outside of the cylinder, means connecting the rod to said last shaft, and means engaging said second shaft and adapted to hold the piston against movement by the spring when the clutch members are in engagement with each other.

10. In combination, the brake cylinder and the primary lever of an air brake, a second cylinder provided with diametrically op-

posed guides extending longitudinally thereof, a piston slidably mounted in said second cylinder and provided with ribs sliding in said guides, rollers carried by one of said ribs and contacting with the guides, means connecting the piston to the lever to permit the movement of the piston in one direction to rock the lever in brake applying direction, a spring adapted to move the piston in said direction, means connected to the other guide rib of the piston and adapted to be operated to move the piston in the opposite direction to compress the spring, and means releasably holding the piston against movement by the spring.

In testimony whereof I hereunto affix my signature.

OTTO HOOVER.
